UNITED STATES PATENT OFFICE.

CLAUDE L. POST, OF CHICAGO, ILLINOIS.

PRINTING APPARATUS.

Application filed June 18, 1925. Serial No. 38,035.

My invention relates to improvements in printing apparatus and particularly to apparatus for removably securing printing devices in a type roll or the like. My invention has among its objects the production of apparatus of the kind described, which is simple, reliable, compact and satisfactory for use wherever found applicable. A particular object of the invention is to provide improved apparatus for removably securing individual type, as distinguished from linotype or printing slugs, in a type roll. Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts;

Fig. 1 is a sectional view through a printing machine having apparatus embodying the invention;

Fig. 2 is a plan view of a type roll shown in Fig. 1 and having type removably secured therein by means embodying the invention;

Fig. 3 is an end elevation of the type roll shown in Fig. 2;

Figs. 4 and 5 are sections taken on lines 4-4 and 5-5, respectively, of Fig. 3; and

Fig. 6 is a perspective of a detail part of my improved apparatus, a portion of said detail part being broken away to illustrate the construction thereof.

I prefer to disclose my present invention in connection with my improved printing machine, which is more clearly shown and described in my co-pending application, Serial No. 741,428, filed October 3, 1924.

The improved printing machine preferably comprises a frame 1, a type roll 3 and a platen or impression roll 4. The impression roll 4 may be provided with a tympan 2 and a feeding arc 2^a arranged to cooperate with the type roll. The envelopes or other

matter to be printed are delivered between the rolls 3 and 4 by suitable means described in the co-pending application, the rolls being driven by other suitable means also described in the co-pending application.

The type roll 3 is designed to carry any desired number of type 5, each type 5 bear-

ing a single character in the illustrated embodiment of the invention. As shown, the roll 3 has a groove 7 therein, the depth of the groove being such that when the type 5 rest on the bottom surface 7^a thereof, the faces of the type will be properly disposed to cooperate with the roll 4. In accordance with usual practice, the side faces of the type are parallel and to maintain them in proper relation in the groove 7 I provide wedge-shaped spacers 8 which properly space and retain the type in printing positions. The spacers 8 preferably extend beyond the end type of each line of type, the lines being completed by quads or blank type bars 5^a. I do not limit myself to the arrangement shown, as, obviously, the spacers could be made to conform to type of any size and shape.

I will now describe the improved apparatus whereby I removably secure the type 5 in the printing roll 3, the printing roll 3 being particularly adapted to cooperate with the improved apparatus and being an essential element of the invention only to the extent indicated in the appended claims.

As best shown in Figs. 1 and 3, the printing roll 3 is provided with wedge-shaped slots 15, one of the wedge-shaped slots 15 being disposed on each side of the groove 7. In each of the wedge-shaped slots 15 I preferably provide a plurality of wedge-shaped members 16, the wedge-shaped members 16 being removably and slidably mounted in the slots 15. The members 16 may be threaded on a rod 17, or the equivalent, which is preferably threaded in opposite directions as indicated at 18 and 19 so that when the rod is revolved it will move the members 16 toward or away from each other. One end of the rod 17 may be squared as at 20 so that it may be engaged by a wrench or the equivalent when it is to be revolved. The members 16 may be provided with projecting parts 21 formed with the inclined faces 22 arranged to engage apparatus described in the co-pending application, which apparatus is not material to the present disclosure.

The members 16 are adapted to hold clamping members 25 in contact with the type 5 disposed in the groove 7. As shown in Fig. 6, each clamping member 25 preferably comprises an arcuate strip 26 having bent ends 27 which may be inserted in the wedge-shaped slots 15, the arcuate strip be-

ing so formed that when the ends 27 are disposed in the slots 15 the strip will snugly fit the printing roll 3. Rigidly secured to the arcuate strip 26 or formed integral therewith is a block or lug 29 adapted to ride in the groove 7, the lug 29 being of less width than the strip 26 so that the overhanging part of the strip may seat on the ends of the spacers 8 and on the top surfaces of the 10 quads filling out the lines of type.

In practice the type 5 and the spacers 8 are first properly positioned in the groove 7. The clamping members 25 are then positioned upon the printing roll 3, the clamping members being slipped on from the ends of the roll. The members 16 and the rods 17 are then positioned in the wedge-shaped slots 15, the rods 17 being manipulated to draw the members 16 tightly against the bent ends 27 of the clamping members which bear against the spacers 8 and quads 5 and prevent accidental displacement of the type 5 relative to the printing roll.

Having thus described my invention, it is 25 obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

35 1. The combination with a type roll having a longitudinal type receiving groove therein, of means slidably mounted on the roll and projecting into the groove for holding the type in adjusted positions therein, and means for clamping said last-mentioned means in the adjusted positions.

40 2. The combination with a type roll having a longitudinal type receiving groove therein, of means slidably mounted on the roll and projecting into the groove for holding the type in adjusted positions therein, and means spaced from the groove for clamping said last-mentioned means in the adjusted positions.

45 3. The combination with a type roll having a longitudinal type receiving groove therein and longitudinal slots arranged one on each side of the groove, of means projecting into the groove and into the slots for holding the type in adjusted positions in the groove, and means disposed in the slots for clamping the last-mentioned means in the adjusted positions.

50 4. The combination with a type roll having a longitudinal type receiving groove

therein and longitudinal slots arranged one on each side of the groove, of means projecting into the groove and into the slots for holding the type in adjusted positions in the groove, and means slidably mounted in the 65 slots for clamping the last-mentioned means in the adjusted positions.

5. The combination with a type roll having a longitudinal type receiving groove therein and longitudinal slots arranged one 70 on each side of the groove, of means projecting into the groove and into the slots for holding the type in adjusted positions in the groove, a plurality of members slidably mounted in each of the slots for clamping 75 the last-mentioned means in the adjusted positions, and means screw-threaded into said members for operating them.

6. The combination with a type roll having a longitudinal groove therein, of type 80 arranged in said groove, spacers arranged between the type, and means engaging the top surfaces of the spacers to prevent radial movement of the spacers relative to the roll and engaging the end surfaces of the spacers 85 to prevent longitudinal movement of the spacers relative to the roll.

7. The combination with a type roll having a longitudinal groove therein, of type arranged in said groove, spacers arranged between said type, and a plurality of means 90 slidably mounted on the roll and engageable with the top and end surfaces of said spacers.

8. The combination with a type roll having a longitudinal groove therein, of type 95 arranged in said groove, spacers arranged between said type, a plurality of means slidably mounted on the roll and engageable with the top and end surfaces of said spacers, and means for clamping said last-mentioned 100 means against the spacers.

9. The combination with a type roll having a longitudinal groove therein, of type arranged in the groove, quads arranged in the groove, the type being disposed intermediate the quads, and means slidably mounted on the roll and engageable with the top and side surfaces of the quads for clamping the type to the roll.

10. The combination with a type roll having a longitudinal type receiving groove therein, of a plurality of spaced means movably mounted on the roll and arranged to project into the groove for holding the type in adjusted positions therein, and means for securing said last-mentioned means in the adjusted positions.

In testimony whereof, I have hereunto signed my name.

CLAUDE L. POST.
